(57) **CLAIM**

The ornamental design for a bottle for packaging fluids for retail, as shown and described.

DESCRIPTION

FIG. 1 is a front perspective view of the bottle for packaging fluids for retail showing the new design, shown in use with exemplary stoppers.

FIG. 2 is a front perspective view of the bottle for packaging fluids for retail of FIG. 1, shown with the exemplary stoppers removed.

FIG. 3 is a front view of the bottle for packaging fluids for retail of FIG. 1.

FIG. 4 is a front view of the bottle for packaging fluids for retail of FIG. 2.

FIG. 5 is a side view of the bottle for packaging fluids for retail of FIG. 1.

FIG. 6 is a side view of the bottle for packaging fluids for retail of FIG. 2.

FIG. 7 is an opposite side view of the bottle for packaging fluids for retail of FIG. 1.

FIG. 8 is an opposite side view of the bottle for packaging fluids for retail of FIG. 2.

FIG. 9 is a rear view of the bottle for packaging fluids for retail of FIG. 1.

FIG. 10 is a rear view of the bottle for packaging fluids for retail of FIG. 2.

FIG. 11 is a top view of the bottle for packaging fluids for retail of FIG. 1.

FIG. 12 is a top view of the bottle for packaging fluids for retail of FIG. 2.

FIG. 13 is a bottom view of the bottle for packaging fluids for retail of FIG. 1; and,

FIG. 14 is a bottom view of the bottle for packaging fluids for retail of FIG. 2.

The broken lines are shown for the purpose of illustrating both parts of the article as well as environmental subject matter of exemplary stoppers. None of the broken lines form part of the claimed design.

1 Claim, 14 Drawing Sheets
